DESIGN FOR A CIGAR MACHINE OR SIMILAR ARTICLE

Henry H. Wheeler, Brooklyn, and James P. Durning, St. Albans, N. Y., assignors to International Cigar Machinery Company, a corporation of New Jersey

Application June 10, 1938, Serial No. 77,715

Term of patent 14 years

To all whom it may concern:

Be it known that we, Henry H. Wheeler, a citizen of the United States of America, residing at Brooklyn, in the county of Kings and State of New York, and James P. Durning, a citizen of the United States of America, residing at St. Albans, in the county of Queens and State of New York, have invented a new, original, and ornamental Design for a Cigar Machine or Similar Article, of which the following is a specification, reference being had to the accompanying drawing, forming part thereof.

The drawing shows in Fig. 1 a front perspective view of a cigar machine, illustrating our new

design; Fig. 2 is a view of the same in rear perspective; and Fig. 3 is an end perspective view, looking from the right of Fig. 2, showing a segregable portion of the machine, comprising the hopper and its associated parts as disclosed in Figs. 1 and 2.

The showing in Fig. 3 constitutes a characteristic feature of the complete design.

We claim:

The ornamental design for a cigar machine or similar article, as shown and described.

HENRY H. WHEELER.
JAMES P. DURNING.
